UNITED STATES PATENT OFFICE

2,187,242

VENETIAN BLIND

Michael L. Kesner, Chicago, Ill.

Application October 6, 1938, Serial No. 233,514

3 Claims. (Cl. 156—17)

This invention relates to Venetian blind constructions of the type illustrated in the patent of Michael L. Kesner, No. 1,951,659 of March 20, 1934, which has the characteristic of V-shaped 5 louver guide channels in side frames. These guide members receive mitered ends of the blind louvers, keeping the louvers in alignment against swaying in any direction or rattling while allowing the louvers to oscillate on their own horizontal axes to open, shut or intermediate positions.

Improvements on the patented construction are herein disclosed, and relate mainly to an alteration of the mounting of the V-channel guide elements, wherein these elements are no longer 15 fixed but constitute the side members of a pivoted louver frame, enabling the entire blind construction to be swung inwardly away from the window frame so as not to interfere with washing and adjustment or repairs to the window.

Other objects of the invention are to provide a Venetian blind construction with an independent 20 expandible and contractible frame whereby the blind unit may be correctly fitted to window frames having a slight variation from standard for the specified size of the window; to provide detail improvements such as the construction for supporting the louver unit and associated with 25 operating means providing for an exact uniform angular adjustment of the louvers around their longitudinal axes; and the provision of friction grip elements of V-section or conical fitting the V-channels and allowing the blind to be freely drawn to any position or to travel up more-or-less under the action of a spring roller, and to 30 be retained in the position where it is released.

The objects of the invention are attained by a construction as illustrated in the drawings wherein:

Figure 1 is a face view of the blind construction installed in a window frame, the latter being shown broken away.

Fig. 2 is an enlarged detail view in horizontal section, as indicated by the line 2—2 of Fig. 1, showing a friction holder for the blind unit.

Fig. 3 is a perspective view of a window frame and blind therein with the adjustable blind frame swung out and held clear of the window.

Fig. 4 is a fragmentary detail in front elevation of a friction holder designed for engagement with channels in which the blind louvers are adjusted up and down.

Fig. 5 is a perspective view of the blind frame structure separated from the window frame.

Fig. 6 is an enlarged fragment of the cross

member of the blind frame to show adjustability thereof.

Fig. 7 is a sectional view taken on the line 7—7 of Fig. 6.

Fig. 8 is a face view of the left end bracket for the blind roller and the leader slat of the blind and includes a fragment in section of the blind unit hinged thereto.

Fig. 9 is a face view of the opposite bracket for the blind roller including a blind adjusting knob 10 and showing in section part of the blind unit including the leader slat or top rail.

Fig. 10 is a fragmentary front view indicating the relationship between the spring roller, top rail of blind unit and support brackets.

Fig. 11 is an end view of a casing for the friction holder.

As indicated by the above-mentioned objects of the invention, the general features of the construction illustrated include, a Venetian blind frame which is adjustable to an angle with the window frame which the blind fits; means for insuring absence of rattle; retention of the blind louvers in any partially collapsed position in their guides; provision for all necessary adjustments for an exact fit to a window; and provision for general ease of manipulation of the blind.

The drawings show the blind construction mounted within a window frame 1. An outer fixed frame 2 of the blind construction is attached to the inner surface of the window frame, inside the window. This outer blind frame 2 includes side elements 3 and an upper transverse frame member 4. At the top side members 3 are flanged over at 5, Fig. 10, to receive through slots 6 30 screws 7. This connection provides for a limited expansion or contraction of the blind frame to compensate for variations in window frame dimensions.

The side elements have welded thereto the 40 brackets 8 and 9, Figs. 8 and 9. Bracket 8 is slotted at 10 for the reception of the square-ended trunnion 11 of a spring roller 12. At its opposite end, the spring roller has the customary round trunnion 13 for fitting the round aperture 45 14 in bracket 9.

A heavy top rail or leader slat 14, Figs. 11 and 12, is also supported by the brackets 8 and 9. At its left-hand end, Fig. 10, the leader slat carries a trunnion 15 fitting opening 16 in bracket 50 8 and at its right-hand end carries a tongue 17 fitting a slot 18, Fig. 9, in an arm 19 of a bent metal segment gear 20. The gear is pivoted on a pin 21 carried by bracket 9 and the teeth of this gear mesh with a worm 22 carried by a rod

23. This rod has a knurled operating head 24, and bearings in ears 25 of bracket 9.

By turning the knurled head, the leader slat 14 is adjusted angularly on its longitudinal axis and through the tapes 26, Figs. 1 and 3, transmits its motion as is customary to the louvers 27. Transverse tie members connect the tapes on opposite sides of the slats and pass above and below the slats so as to positively transmit motion from the leader slats to the others.

The spring roller 12 is permitted to operate to draw the slats upwardly by squeezing the grips 29 of a friction-holding device 30 shown in Figs. 1, 2 and 4. This holding device carries friction cones 28 of Fig. 3, or the elongated beveled friction elements 31 of Figs. 1, 2 and 4, for engagement with guide channels 32 for the louvers. The friction elements are preferably made of rubber and are pressed outwardly by springs 33.

20 The guide channels 32 are formed in louver frame elements 34 and 35 which are hung from the side members 3 of fixed frame 2, by pivot pins 36 and 37.

25 The channel members 34 and 35 are connected at their lower ends by a multi-part transverse frame member 38 constructed for lengthwise expansion or contraction, as illustrated in Figs. 5, 6 and 7. Screws 39 are accessible through openings 40 in the members 41 of transverse frame 30 38 through slot 42. The interfitting elements of this lower frame may be slid slightly lengthwise of each other and then clamped together by screws 39. This allows for the inner louver-carrying frame to be adjusted according to the adjustment of the outer bracket carrying frame 2.

The hinged blind unit is normally retained in the vertical position by spring bullet latches 43, Fig. 3, which engage recesses 44 in the blind frame.

45 The blind may, however, be swung outwardly as indicated in Fig. 3 and retained in that position by arms 45 which are pivoted at 46 to a bracket 47 welded to frame structure 2. These arms are normally suspended in vertical position out of view but may be positioned to engage notches 48 in the louver guide elements 34 and 35.

50 The friction holding device 30, shown in Fig. 4, is known as a curtain or blind fixture and the common construction includes a pair of spring-pressed elements for engagement with the window frame. In the disclosure now made that construction is modified so that the friction elements 31 are of suitable cross section to travel in and engage the V-channels 32. Elements 31 carry guide pins 49 slidable in apertures formed in a wood casing 50 for fixture 30. This fixture also provides an anchoring means for metallic tapes 51 which lead from the fixture upwardly 55 through slots in the louvers to the spring roller 12. The metal tapes 51 are preferably located to be covered by the ladder tapes 26.

55 The operation of the construction is similar to spring roller shades in that it is drawn down by 60 grasping the grips 29. When these are released

the friction holding device retains the blind in the set position. To allow the blind to be drawn up toward its folded position by spring roller 12, the grips 29 are pressed toward each other. Another feature of operation of the device is imparting the desired tilt to the louvers through turning the knurled head 24. The worm 22, by engagement with segment gear 20, turns the leader slat 14 and the angular adjustment given to the leader slat is communicated through the ladder tapes 26 to the louvers 27.

5 The blind and its frame structure may be swung on its pivots 36 and 37 clear of the window in an inward direction and retained in the moved position by arms 45. Access to the window may thus be had without interference from the blind.

10 The V-channelled frame structure which swings from the fixed frame constitutes a support for each and all of the louvers holding them against sag when the blind is swung inwardly from the fixed frame, and serve as guides for the louvers when they are slid upwardly or downwardly and also serve as end bearing supports for the louvers when the louvers are turned angularly on their longitudinal axes.

15 The ladder tapes 26 are secured to what is known in the art as upper and lower rails. The lower rail, generally constructed about the same as a louver, but heavier and the upper rail, herein referred to as the leader slat, are turnable as a unit with the louvers on their longitudinal axes.

20 I claim:

1. A blind construction of the class described including a set of louvers with flexible suspension connections between the louvers, a frame structure for the louvers including channel elements of V-section for guiding the louvers, and resiliently mounted conical grip elements connected with the louvers and engageable with the V-channels for retaining the louvers in any desired set position in the blind frame.

2. A Venetian blind construction including a set of louvers with flexible suspension connections between the louvers, a frame structure for the louvers including channelled guide elements of V-section for guiding the louvers, and resiliently mounted V-section grip elements connected with the louvers and engageable with the V-channels for retaining the louvers in any desired set position in the blind frame.

3. A Venetian blind construction comprising a fixed frame having vertical side elements and a horizontal connecting member between the tops of said side elements, said horizontal connecting member having connections with said side members providing for adjustment of the lateral spacing of said side members, a U-shaped blind guiding frame having side members pivoted at their upper ends to the fixed frame and a bottom connecting member formed of relatively slidible elements whereby the spacing between the side members of the blind guiding frame may be varied.

MICHAEL L. KESNER.
